UNITED STATES PATENT OFFICE.

ARTHUR R. SURPLUSS, OF CHICAGO, ILLINOIS.

POWER-APPLYING DEVICE.

Application filed January 9, 1925. Serial No. 1,332.

This invention relates to power storing and applying devices, and it has particular relation to a device of the character designated wherein a constantly, or substantially constantly, applied small amount of power is transmitted through a system of novel leverages and stored to accumulate a large amount of potential energy, the last mentioned energy being utilized for various purposes.

10 The apparatus which is hereinafter described may be utilized in a variety of different associations to obtain the required storage of energy and application of power and, although the application of the device is 15 described in connection with an intermittently applied force such as may be taken from a particular mechanical device capable of delivering power, it should be understood that the invention is capable of use in connection with many different mechanical apparatuses such, for instance, as drop-hammers, timers for the flow of materials, time-locks, time-controls for furnaces, speed indicators and measuring devices, jacks of all kinds, 25 adding machines, and any other mechanisms wherein it is desired to periodically indicate conditions which have occurred over a space of time, or changes of condition after a period of time.

30 A further object of my invention is to provide a device of the above character wherein the operation is effected by gravity, and the stored-up energy of spring devices does not have to be relied upon. A device of the character hereinafter described is, therefore, far more accurate and positive in operation.

The invention will be better understood by reference to the accompanying drawings, in which:

40 Figure 1 is a perspective elevational view of a preferred form of mechanism embodying the invention;

Fig. 2 is a plan view of the apparatus shown in Fig. 1;

45 Fig. 3 is an elevational view of a portion of the device illustrating one feature thereof which especially contributes to the desirability and accuracy of operation of the device;

50 Fig. 4 is an elevational, sectional view taken from one side of the device, this side being the backside of the device as shown in Fig. 1;

Fig. 5 is an elevational, sectional view taken on the line 5—5 of Fig. 2;

55 Fig. 6 is an elevational, sectional view taken on the line 6—6 of Fig. 2;

Fig. 7 is a fragmentary side elevational view of a further development of a portion of the device shown in Fig. 1;

Fig. 8 is an end elevational view of the structural portions shown in Fig. 7; and

Fig. 9 is an elevational end view of certain of the gear wheels in the device illustrating the manner in which they may, at times, lock.

Referring now more particularly to the drawings, the device in the preferred form shown, may embody two plates 9 and 10, said plates being connected together near their top by beam-like members 11 and 12 whereby a rigid frame is eventuated for the device.

In Fig. 1 the device is shown in perspective, and in so doing plate 10 is entirely removed, it being understood that, as viewed in Fig. 1, we are looking at that side of the machine which is at the top in Fig. 2. It will further be understood that the various instrumentalities which are hereafter described, such as shafts and beams, and which extend from plate to plate and are journaled therein, extend through, or to, the plate 10 which has been removed in Fig. 1.

A shaft 13 extends between the beam members 11 and 12, and is supported through precision bearings 14 and 15 respectively (Fig. 5) set into said beams. Mounted on the shaft 13 is a worm 16, which latter engages a large gear wheel 17. This last named gear wheel 17 is mounted on a shaft 18, which latter is journaled in precision bearings set into the side frames 9 and 10, these being of the same character as is illustrated in connection with the shaft 13. There is, therefore, an initial multiplication of mechanical advantage by the worm and wheel. While a worm is described and hereafter referred to, it should be understood that a spiral gear may be used if desired instead of a worm without departing from the scope of the invention.

Abutment brackets 19 and 20 are rigidly secured near the outer edge of the gear wheel 17, these abutments carrying at their outer ends rollers 21 and 22 respectively. It will be noted that the upper abutment is not quite in a diametrical line with the lower abutment, or in other words, that the angular measurement between them is not the same in both directions. The purpose of this inequality of disposition of abutments will be hereinafter explained, and it should be now noted that this is one of the particular features of the present apparatus which commends it for use in connection with an indi-

cating mechanism, for instance with meters of various types whereby an accurate indication of the amount of material metered will be obtained, even though the mechanism 5 herein described must, of necessity, take some time to register.

An angular arm 23 is pivotally mounted in the frame members 9 and 10 on 24, said arm having a segmental gear 25 formed integrally 10 therewith. The upwardly extending portion 26 (see Fig. 1) of the aforesaid arm terminates in a planer bearing member 27 upon which the rollers 21 and 22 may ride.

Mounted in parallel and coaxial relation 15 with the arm 23 is an independently revolvable gear 28 which meshes with a small gear 29. The small gear 29 serves to rotate a shaft 30, and in the embodiment of the invention which is here described, it is from this 20 shaft 30 that the stored potential energy is taken, and this shaft 30 is, therefore, hereafter designated as a work shaft.

As best shown in Fig. 9, the gear 28 has a circular ratchet 31 rigidly mounted thereupon, this ratchet cooperating with dogs 32-32 which are pivotally secured to the segmental portion 25 of the arm 23 whereby said dogs 32 ride over the ratchet teeth 31 when the arm moves in one direction and engage with said ratchet teeth when the arm moves in the other direction, for purposes hereinafter described, in connection with the operation of the device.

In connection with the aforesaid dogs 32, it 35 should be noted that one is set slightly in advance of the other, that is, when one dog is engaging the base of a tooth the other is approximately half-way along the tooth. This feature is introduced to provide for the minimum of lost motion in the device whereby the 40 same is rendered exceedingly accurate in operation. If both dogs occupy the same position with respect to the root or base of the tooth, there is a possibility of lost motion to the extent of one ratchet tooth, particularly if both pawls should happen to start their actuating movement at the apex of the two teeth which said pawls are about to engage. However, when one pawl is set at the apex of a 45 tooth and the other about half-way between the apex and base of a tooth the total possible lost motion is one-half tooth only. The provision of two pawls, therefore, and the setting of the same as just described eventuates 50 a very accurate machine in that lost motion is substantially reduced and also gives a measure of safety to the machine.

A weight 33 is mounted on pins 33^a and 33^b in the side frame 10 and has teeth thereupon 55 which engage with the teeth of the segmental gear 25 whereby a downward movement of the arm 23 functions to raise said weight 33 to the upper limit of its movement (see Figs. 1 and 6).

60 The operation of the improved device is as

follows, it being assumed for purposes of illustration only, that the power storing and applying device embodying the elements above described, is used in connection with some sort of device which has an intermittently or 70 constantly moving member, and where it is desired to accumulate the small increments of energy received from the intermittently or constantly moving member into a considerably greater power, which latter is periodically imparted to the work shaft, for this purpose it is assumed that a member 34 is intermittently or constantly movable to actuate the worm 16 through a dog 35 and a ratchet wheel 36. 80

The worm 16 is, therefore, intermittently turned and in so doing turns the wheel 17. As the latter turns, the rollers 21 or 22 press the arm 23 downwardly around the pivot 24, and through the intermeshing of the segmental gear 25 and the teeth on the weight 33, the latter is raised and the energy thus transmitted is stored for future application. When the arm 23 has reached its lowermost position, the rollers 21 or 22 ride off the inner end of the bearing surface 27, thereby releasing the arm and allowing the weight 33 to pull the arm upwardly. As the arm travels downwardly, the dogs 32 ride over teeth 31 and no movement is communicated to 95 the aforesaid teeth 31, or the gear 28 rigidly secured to the latter. When, however, the weight moves downwardly under the influence of gravity, it being remembered that this latter occurs when the arm 23 is released, 100 the dogs 32 engage the teeth on the member 31 and quickly turn the gear 28 in a clockwise direction (Fig. 1), the turning of this gear in turn rotates the small gear wheel 29 and the work shaft 30. It follows, therefore, 105 that the power, which, through substantially the half revolution of the gear 17, has been gradually stored up as received from the intermittent motion of the member 34, is markedly multiplied and applied to the 110 shaft 30.

Upon the shaft 30, therefore, may be mounted any instrumentalities which it is desired to move through application of an intermittent but constantly applied force on 115 the shaft 13. As hereinbefore indicated, the abutments 19 and 20 are not in a diametrical line for the reason that an appreciable time is taken while the arm moves back up into juxtaposition with the next roller, and if the 120 abutments or rollers were exactly opposite each other an error would result, since that quantity of movement which occurred on shaft 13 during the return of the arm would be lost. However, by arranging the rollers 125 as described, in that they are not seated along a diametrical line, this loss is prevented since the same is compensated at every complete revolution of the wheel 17. In other words, what is lost during one interval of arm oper- 130

ation is compensated during the next interval of arm operation.

As hereinbefore indicated, the shaft 30 may carry various instrumentalities, and since the 5 inertia of these may be such that the shaft 30 is not stopped at the desired point when the arm returns to its upward position, a mechanism for insuring an exact 360° revolution of the shaft 30, but no more, is provided, as illustrated in Fig. 3.

Keyed to the shaft 30 is a lug or stop 37 which, while the shaft 30 is in stationary position, is disposed downwardly, as shown in Fig. 3. A pin 38 is fixed on the weight 33, 15 which pin, upon the raising of the weight, strikes against the right-hand end 39 of the pivotally mounted lever 40. The lefthand end 41 of lever 40 is against the lug 37 whereby the shaft is positively prevented from 20 turning in an anti-clockwise direction as long as said lever 40 is in the position shown. Immediately, however, before the weight 33 reaches the uppermost position and the arm 25 33 is released and starts to return to the position shown in Fig. 1, the pin 38 strikes the lever 40 and turns it so that the lefthand end 41 thereof is no longer in the way of the lug 37. The shaft 30 is then free to be turned by downward movement of the weight 33 and 30 the consequent movement imparted to the gear 28. Immediately, however, the pin 38 releases the lever 40, the latter, by reason of the end 39 being weighted, moves downwardly into the position shown in Fig. 3 and occupies 35 that position before the shaft 30 has an opportunity to make a complete revolution. Since the lever is, therefore, in the position shown in Fig. 3, the shaft 30 will be positively stopped upon the completion of one 40 revolution. While but one shaft 30 is discussed in the above description it is apparent that a plurality of such shafts may be moved by the gear wheel 28, whereby more than one set of mechanism may be actuated through 45 the latter.

In order to further insure a positive return of the shaft 30 to the proper position, there is provided another weighted and pivoted lever 44, which may turn about a pivot 45, 50 because of its weighted end 46, as the weight 33 moves upwardly. A pin 47 normally holds the lever 44 in the position shown in Fig. 3, in which position an elongated lug 48 bears 55 against the lug 37 and holds it positively in the position shown.

In the operation of the device, as the weight 33 moves upwardly the pin 47 releases the lever 44 and allows said lever to swing, under the influence of the weighted end 46, so that 60 the upper end of the lug 48 is withdrawn from the circular path of the lug 37. A pin 49 is positioned at the left of the elongated member 48. When the upward movement of the pin 47 allows the member 48 to swing to 65 the left, the latter rests against the pin 49.

When, therefore, the weight 33 moves downwardly the pin 47 moves the lever 44 back into the position shown in Fig. 3. If the shaft 30 for any reason should not return all the way to the position shown in Fig. 3, the upper 70 end of the elongated lug 48 engages the lug 37 on said shaft 30 and positively moves it into the position shown in Fig. 3, this positive movement being effected by the pin 47 moving the lever 44 downwardly. 75

While the shaft 13 is described as rotated through the cooperation of an intermittently or constantly movable member 34, a dog 35, and a circular ratchet 36, it should be pointed out that this apparatus may be further 80 elaborated to provide for movement through still another storing means, this last named structure being shown in Figs. 7 and 8. In these latter figures the dog 35 is illustrated as being pivotally mounted on the lower end 85 of a lever 42, this latter is pivoted on a member 43 secured to the frame member 9. The intermittently or constantly movable member 34 is secured to the upper end of the lever 42, and it will be seen that by this 90 method the force applied can be again multiplied in this ratio, which ratio may be still further increased by appropriate lengthening of levers, or otherwise.

While but one embodiment of the power 95 applying and storing mechanism is illustrated, and that only in connection with one possible use of the same, it will be understood that the foregoing device is a unitary self-contained apparatus which may be applied to a variety of different uses, and it is desired, therefore, that the invention disclosed be restricted only by the appended 100 claims and by the scope of the prior art.

Having described my invention, what I 105 claim as new and desire to secure by Letters Patent of the United States is:

1. In an apparatus of the class described, actuating means moved by a small amount of power, a worm and wheel driven thereby, an oscillatory arm actuated by said wheel, a work shaft at which a large amount of power is to be developed, and means connecting said arm to said work shaft. 110

2. In an apparatus of the class described, actuating means moved by a small amount of power, a work shaft at which a large amount of power is to be developed, and multiplying means between said actuating means and said work shaft comprising a worm adapted to receive small power impulses, means for storing up said impulses, and a leverage system for periodically applying said stored up power to said work shaft. 115 120

3. In an apparatus of the class described, actuating means moved by a small amount of power, a work shaft at which a large amount of power is to be developed, and multiplying means between said actuating means and said work shaft comprising a worm adapted to re- 125 130

ceive small power impulses, a gear wheel driven thereby, a pivoted arm actuated by said gear wheel, a weight raised by said arm when the latter moves in one direction under the influence of said wheel, means for periodically releasing said arm and allowing said weight to fall and impart multiplied power to said work shaft.

4. In an apparatus of the class described, actuating means moved by a small amount of power, a work shaft at which a large amount of power is to be developed, and multiplying means between said actuating means and said work shaft comprising a worm adapted to receive small power impulses, a gear wheel driven thereby, a pivoted arm actuated by said gear wheel, a weight raised by said arm when the latter moves in one direction under the influence of said wheel, means for periodically releasing said arm and allowing said weight to fall, means interposed between said weight and said work shaft whereby the latter is moved only during the released movement of said arm.

5. In an apparatus of the class described, actuating means moved by a small amount of power, a work shaft at which a large amount of power is to be developed, and multiplying means comprising a weight adapted to be raised by said small power impulses, and to thereafter fall and thus impart its stored up power to said work shaft, and means for positively insuring but one complete rotation of said work shaft upon each fall of said weight and guarding against an overthrow because of the inertia of said work shaft, said means comprising a stop for said shaft, said means synchronized with said weight to be non-effective when said weight starts to fall thereby releasing said work shaft and thereafter returning to stopping position before said weight completes its power imparting movement, or said shaft makes one complete rotation.

6. In an apparatus of the class described, actuating means moved by a small amount of

power; a work shaft at which a large amount of power is to be developed, and multiplying means comprising a weight adapted to be raised by said small power impulses and to thereafter fall and thus impart its stored-up power to said work shaft, and means for positively insuring but one complete rotation of said work shaft upon each fall of said weight and guarding against an overthrow because of the inertia of said work shaft, said means comprising a stop keyed to the work shaft, and a lever pivoted to normally lie in the path of said stop and prevent the rotation of said shaft, a pin on said weight which raises said lever out of the path of said shaft stop just prior to the downward movement of said shaft thereby releasing said shaft, said lever being adapted to return to normal position before said shaft has completed one revolution and to be then so disposed as to engage said stop to prevent said shaft from making more than a complete revolution.

7. In an apparatus of the class described actuating means moved by a small amount of power, a work shaft at which a large amount of power is to be developed, and multiplying means comprising a weight adapted to be raised by said small power impulses and to thereafter fall and thus impart its stored-up power to said work shaft, and means for positively insuring a complete revolution of said work shaft upon each fall of said weight and guarding against an overthrow because of the inertia of said shaft, but at the same time requiring that said shaft does not stop short of a complete rotation, said means comprising a stop controlled by the falling weight for positively arresting said shaft after it has completed one revolution, and a lock member also controlled by said weight for positively requiring that said shaft make at least one complete revolution.

In witness whereof, I have hereunto subscribed my name.

ARTHUR R. SURPLUSS.
